UNITED STATES PATENT OFFICE.

ANTON POLLAK, OF PARIS, FRANCE.

VOLTAGE-REGULATOR.

1,137,019.

Specification of Letters Patent. Patented Apr. 27, 1915.

Application filed July 18, 1912. Serial No. 710,234.

To all whom it may concern:

Be it known that I, ANTON POLLAK, a subject of the King of Hungary, residing at 7 Avenue due Coq, Paris, in the French Republic, have invented certain new and useful Improvements in Voltage-Regulators, of which the following is a specification:

It frequently happens that dynamos are driven by means of various machines running at variable speeds. This case arises in particular when it is desired to light the interior of vehicles by electricity produced by the engine, for example in the case of automobiles. These dynamos are subjected to very great variations of speed and consequently give a very variable voltage which even becomes *nil* when the engine stops. It is, however, necessary to have a constant voltage, that is to say to limit the voltage furnished by the dynamo to a certain maximum independently of its increase of speed. As in the various applications of the dynamos of the above type it is necessary to add to them a battery of accumulators imparting the desired voltage to the circuit when the dynamo is not running or is furnishing a current of a lower voltage than it is desired to utilize, while on the other hand they are charged by the dynamo when the latter gives a sufficient current, it is also necessary to cut out the accumulators automatically when the voltage of the circuit falls beyond a certain amount below which the accumulators would discharge onto the dynamo.

The present invention has for its object a system which is very simple and strong and is able to withstand the most violent shocks without the least disturbance.

The accompanying drawing illustrates a system according to the present invention. It consists broadly of a coil A, the winding of which is in shunt on the main circuit. This coil A contains at its upper part a fixed core A' and at its lower part a movable core A"; an insulating projection a' prevents the two parts of the core from coming into contact. An armature B pivoted at b with two arms of which B' is adapted to be attracted by the core A' and prevented from coming into contact by means of the insulating stop b', while the arm B' carries a contact b² which normally bears upon another contact b³ by means of a spring C, the tension of which is regulated by means of a screw C'. A spring b⁴ limits the movement of the armature B. The part B² of the armature B and the contacts b² and b³ are interposed in the excita-

tion circuit (shunt E of the dynamo). A resistance D is interposed in the excitation circuit when the two contacts b², b³ are separated; when they are in engagement they short circuit the resistance. The movable core A² of the coil A is prolonged by a rod a², the head a³ of which displaces the lever F pivoted at f¹ and carrying a contact f; opposite the contact f there is another contact g carried by a spring G the tension of which is regulated by a screw g'. The lever F and the spring G are interposed in the circuit supplying the accumulators, the contacts f g closing this circuit.

The apparatus acts in the following manner: The various parts being arranged in the manner described and as shown in the drawing, if the coil A is excited, the core A² will approach the core A' and carry the lever F with it. The latter on being lifted sufficiently for a given voltage, presses one contact against the other in accordance with the degree of attraction between the stationary core and the movable core. However if the voltage of the current generated by the dynamo drops below the limit the two contacts are then separated and the accumulators H are cut out of circuit. The small resistance R between the dynamo and the accumulators accelerates the operation of this device. The insulating projection a' prevents, as already mentioned, the two cores from adhering one to the other. The contact g is fixed on the spring G which balances the residual magnetic action of the core A². If the voltage produced by the dynamo I exceeds a certain limit the core A' exerts upon the armature B' sufficient attraction to overcome the action of the spring C. The contacts separate and the excitation current passes through the resistance D. The excitation then decreases and also the voltage of the circuit. The coil ceases to attract the armature B', the contacts close and the same operations are repeated. It has already been proposed to use for regulating the voltage, coils containing a stationary and movable core, but in such arrangements the movable core regulates the voltage of the machine while the stationary core merely serves to intensify the action of the former core. According to the present invention however the voltage is regulated by the stationary core while the movable core is capable of a twofold action, namely, it closes the contacts of the switch controlling the cutting in and out of the accumulators in the work

- circuit and also influences the regulation of the dynamo voltage, as a separate part independently of the tractive spring of the oscillating interrupter armature. By reason of the air space the constant value regulation is begun later, that is at a higher voltage, than would otherwise be the case, so that a correspondingly increased tractive force is exerted upon the movable core so that on the one hand the switch contact is not liable to be affected by reason of sudden jerks or shocks and on the other hand strong springs may be employed to separate the fixed and movable cores even should there be a small fall in voltage.

When the speed of the dynamo I (which is of course independent of the load itself and depends only upon the speed of the motor of the vehicle) is above the normal speed, that is the speed at which the dynamo can maintain the voltage notwithstanding the load, no disturbance arises at the contact closing device. However under no load the dynamo may run at a speed below the normal so that the voltage is sufficiently high to cause the attraction of the core A^2 , but as soon as the accumulators are switched in the voltage drops to such an extent that they are cut out of circuit, and so on. In this position a vibration of the contacts g and f might arise and exert a harmful action thereon. In order to avoid this defect, an additional pair of contacts g^2 are arranged and they are directly connected with the working circuit (the accumulators) while between the contact g and the accumulators a small resistance R is interposed. When the core A^2 rises the accumulator circuit is first of all switched in with the dynamo (the main circuit) by the resistance R and the dynamo is fully loaded by the contact g^2 when the voltage rises notwithstanding the preliminary load ($R H$), that is to say when the speed is sufficiently high to maintain the voltage. In switching off, the load is also removed only partly by the contact g^2 while the whole load is removed by the contact g only then when the speed is not sufficiently high to attract the core A^2 even under no load.

What I claim and desire to secure by Letters Patent of the United States is:

1. A voltage regulator for variable speed dynamos comprising in combination, a switch to close and open the dynamo circuit respectively when the voltage exceeds and drops below a certain limit, a shunt circuit, a spring controlled oscillating interrupter armature interposed in said circuit and a single coil interposed in another circuit, a stationary core arranged in said coil and adapted to regulate the dynamo voltage by the operation of said interrupter arma-

ture, and a movable core likewise arranged in said coil and adapted to operate said switch and to influence the regulation of the dynamo voltage, as a separate part, independently of the spring of said oscillating interrupter armature in such a manner that the voltage is regulated to a given value exceeding the normal voltage until the movable core reaches its final position.

2. A voltage regulator for variable speed dynamos comprising in combination a work circuit extending from the dynamo, a single coil arranged in shunt from said circuit and containing a fixed and a movable core, a switch operated by said movable core to cut accumulators automatically into and out of circuit with said dynamo, said switch comprising main contacts, an additional contact between said main contacts and said work circuit, and a resistance through which the work circuit is connected with the dynamo when said switch is preliminarily attracted and when the main contacts are in engagement, and which resistance is short circuited during further movement of said movable core toward said fixed core and when the additional contact is in operation.

3. A voltage regulator for variable speed dynamos comprising in combination, a work circuit extending from the dynamo, a single coil arranged in shunt from said circuit and containing a fixed and a movable core, a main resistance, an interrupter armature operated by said fixed core to throw the resistance into and out of the excitation circuit under determined conditions, a switch operated by movable core to cut said accumulators automatically into and out of circuit with said dynamo under determined conditions, said switch comprising main contacts, auxiliary contacts between said main contacts and said work circuit, and a resistance through which the work circuit is connected with the dynamo when said switch is preliminarily attracted and when the main contacts are in engagement, and which resistance is short circuited during further movement of said movable core toward said fixed core and when the auxiliary contacts are in engagement, the said resistance being cut into the work circuit during a given return movement of said movable core and cut out of circuit only during a further return movement of said movable core, thereby obviating the vibration of the main contacts by a step-by-step switching in and out of operation.

In testimony whereof I affix my signature in presence of two witnesses.

ANTON POLLAK.
